UNITED STATES PATENT OFFICE.

CHARLES R. SAYRE, OF HAMPTON, VIRGINIA.

STEAM-BOILER.

SPECIFICATION forming part of Letters Patent No. 717,981, dated January 6, 1903.

Application filed March 12, 1902. Serial No. 97,809. (No model.)

To all whom it may concern:

Be it known that I, CHARLES R. SAYRE, a citizen of the United States, residing at Hampton, in the county of Elizabeth City and State of Virginia, have invented certain new and useful Improvements in Steam-Boilers; and I do hereby declare the following to be a full, clear, and exact description of the invention, such as will enable others skilled in the art to 10 which it appertains to make and use the same.

The invention has for its object to provide a boiler having a large surface of heating area and a quick circulation of the water due to the construction of said boiler.

15 A further object of the invention is to make a boiler simple in construction, cheap in first cost, readily of repair, safe in use, and economical in fuel.

The invention consists of a central main 20 vertical drum having steam and water spaces. This drum is surrounded by one or more series of drums or flat corrugated independent sections, each of said sections being independently connected to the water and steam 25 spaces of the main or central drum, the outer series being placed close together to form a wall to conduct the heat to the top of the boiler, all the sections being immediately in contact with the heat of the furnace, the said 30 outer wall series being connected with the water fire-box and the central drum through which circulation is established.

In the accompanying drawings, Figure 1 shows a vertical section of my boiler and its 35 casing and connection. Fig. 2 is a horizontal section through line X X in Fig. 1; Fig. 3, a perspective view of the corrugated fire-box with part broken away. Fig. 4 is a view of 40 one of the smaller corrugated drums or sections.

The same letters of reference indicate the same part in all the figures of the drawings.

In the drawings, A represents the central or main drum, and B B the smaller flat corrugated drums. These drums are arranged 45 in spaces concentrically around the main drum and are connected thereto near their top and bottom by the tubes a a, the outer series of drums, which form the wall, being 50 connected to the main drum near its ends, and each section of tubes of the inner series

are connected to the main drum between these points.

The main drum is provided with heads c c, which are secured by through-bolts b, and to 55 the top head is secured the steam-pipe C.

Within the steam-space of the main drum is the deflector D, which is conical in form and inverted, the upper edge d of which is curved to form a lip and is located above the 60 uppermost ends of tubes a a to prevent any water accumulating in the deflector. A hole f is provided in the bottom, which forms an eddy to cause the water to separate from the steam. 65

The outer series of smaller drums are so connected to the main drum that they will be in contact with each other, and thereby form a wall for the furnace and between it and the boiler-covering, forming a downdraft-flue. 70

The smaller drums may be of any form; but I prefer to make them in one piece or cast and approximately flat and being corrugated on both sides, thereby presenting a greater amount of heating-surface in proportion to 75 the space which they occupy.

The outer series of sections, which form the wall of the furnace, rest upon the water corrugated fire-box E and are free to permit the expansion and contraction. A number of the 80 sections in the series are connected to the fire-box by the pipes e e to permit the feed-water, which enters the pipe F, to pass into the water fire-box and which is a preliminary heater for the water entering all the drums or sections and also for circulation. The usual blow-off may be used. The water fire-box 85 also serves for a mud-drum.

Some distance over the fire-box I locate an annular plate 1, which fits around the outer 90 circle of tubes or sections and about, against, and held in place by the outer casing. The plate 1 horizontally divides the space occupied by the outer sections and the casing and permits the lower ends of outer section on 95 both of their sides to be in direct contact with the heat of the furnace and also compels the heated gases to pass up between the sections and around, over, and down the outside of the outer section to the uptake. 100

The boiler is provided with a casing G, which may be made of any non-conducting

covering. It will be observed that the water fire-box has four feeding-doors, but may have a more or less number, if desired. The openings *h* for these doors pass over the water-space of the fire-box, the upper portion of which is formed of a sharp bevel or inclined all around its periphery for the purpose of forming a coking-chamber, by means of which the green gases are extracted from the coal and passing over the incandescent flame are consumed, thus consuming all the gases as well as preventing smoke. Of course the magazine coal-feeding openings are provided with properly-arranged doors. It will also be observed that a flange or rim *J* is formed around the top of the fire-box for the reception of the casing. This rim may be dispensed with and the fire-box terminate in knife-edge form, the bosses *k* being sufficient to bear the weight of the boiler when connected by union or well-known joints. In this case the edge of the outer casing will coincide with the outer edge of the fire-box.

In the lower part of the casing near the fire-box is the smoke-pipe *I* for conveying off the smoke, the heat already having passed around and between the sections, as described.

From the foregoing description the operation of the boiler will be readily understood. The fire being started, the outer series of drums forming the furnace-wall will cause the heat from the fire to ascend around and above all the sections and to the top of drums and surrounding the same, and then after passing down between the outer sides of the outer series of drums or sections and casing to the smoke-pipe *I*, the outer series of sections and the inner side of the casing forming a flue, the heat will cause the water to circulate from the bottom of the main drum through the smaller drums to the top of the main drum, permitting the free escape of steam and keeping an even temperature of water in the boiler. Should any water be carried through the upper pipes *a* during the circulation or escape of steam from the smaller sections of drums, it will come in contact with deflector *D*, separating it from the steam, thus preventing it from being carried off with the steam as it passes out of pipe *C*. It will be seen that the boiler can be used for a hot-water boiler, as the water can pass up through pipe *C* to the heating system and back from the same through pipe *F*. Of course the deflector would not be needed in that event.

It will be observed that the size of the boiler may be increased or diminished by adding or decreasing the number of sections; but in either case the outer row of drums or sections will be placed edge to edge to form the wall

which between it and the casing forms the escape-flue for the smoke.

Having thus described my invention, what I claim is—

1. In a steam-boiler the combination of a central drum with a concentric series of smaller drums or sections, each drum of the series being connected at the top and bottom to the central drum and the outer series forming the wall of the furnace. 70

2. In a steam-boiler the combination of a central drum with a concentric series of smaller drums, each drum of the series being connected at the tops and bottom to the central drum and a water fire-box the outer series resting on the fire-box, and forming the wall of the furnace. 75

3. In a steam-boiler the combination of a central drum with a concentric series, of smaller drums connected at the top and bottom to the central drum, and water fire-box the outer series of drums resting on the fire-box, and connected to the same for circulation of the water by one or more tubes. 80

4. In a steam-boiler the combination of a central drum with a concentric series of smaller drums connected at the top and bottom to the central drum a water fire-box the outer series of drums forming a wall for the furnace for the fire-box, and resting on the same, and a water connection between some of the drums of the outer series and the water fire-box. 85

5. In a steam-boiler the combination of a central drum with a concentric series of smaller drums, and a deflector in the top of the central drum; each drum of the series connected at the top and bottom to the central drum by tubes; the upper edge of the deflector being above the upper tubes leading from the smaller drums. 95

6. In a steam-boiler the combination of a central drum with a concentric series of smaller drums each drum of the series being connected to the central drum, and a casing for the boiler, the outer series of drums forming a wall for the furnace, and with the casing forming a downdraft-flue for the boiler. 105

7. In a steam-boiler the combination of a central drum with concentric series of smaller corrugated flat drums, each drum of the series being connected at the top and bottom to the central drum and the outer series forming the walls of the furnace. 110

In testimony whereof I affix my signature in presence of two witnesses.

CHARLES R. SAYRE.
